US00D978205S

(12) **United States Design Patent** (10) Patent No.: **US D978,205 S**
Burke et al. (45) Date of Patent: **** Feb. 14, 2023**

(54) **REFRIGERATOR SHELF**

- (71) Applicant: **WHIRLPOOL CORPORATION**,
Benton Harbor, MI (US)
- (72) Inventors: **Julia B. Burke**, Chicago, IL (US);
Mansour Ourasanah, Chicago, IL
(US); **Daniel H. Quinlan**, Stevensville,
MI (US)
- (73) Assignee: **WHIRLPOOL CORPORATION**,
Benton Harbor, MI (US)
- (**) Term: **15 Years**
- (21) Appl. No.: **29/837,572**
- (22) Filed: **May 6, 2022**

Related U.S. Application Data

- (60) Continuation of application No. 29/796,231, filed on Jun. 23, 2021, now Pat. No. Des. 954,767, which is a continuation of application No. 29/729,510, filed on Mar. 27, 2020, now Pat. No. Des. 926,235, which is a division of application No. 29/629,155, filed on Dec. 12, 2017, now Pat. No. Des. 883,348, which is a division of application No. 29/541,982, filed on Oct. 9, 2015, now Pat. No. Des. 808,446.

(57) **CLAIM**

The ornamental design for a refrigerator shelf, as shown and described.

DESCRIPTION

FIG. 1 is a perspective view of a refrigerator shelf according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The portions of the article shown in even broken lines form no part of the claimed design.

Dash-dot-dash broken lines adjacent un-shaded areas represent bounds of the claimed design and form no part of the claimed design themselves.

1 Claim, 5 Drawing Sheets
